UNITED STATES PATENT OFFICE.

THOMAS F. HATTON, OF INDIANAPOLIS, INDIANA.

OIL HEATER.

Application filed September 18, 1922. Serial No. 589,020.

To all whom it may concern:

Be it known that I, THOMAS F. HATTON, a citizen of the United States, residing at Indianapolis, in the county of Marion and 5 State of Indiana, have invented new and useful Improvements in Oil Heaters, of which the following is a specification.

This invention relates to heating devices in which oil is used for fuel; and the objects 10 are, first, to provide an economical heating device where oil is used, that may be variously proportioned, as in a small stove to heat a room or two, or in furnaces to heat several rooms or an entire house; second, to 15 provide greatly increased radiating surface; third, to insure circulation which will always take the cold air from below the heater through the heater and discharge it above in a heated condition; fourth, to provide 20 means for conserving the heat and for applying it more uniformly to the circulatory system of the heater; fifth, to prevent the waste of any overflow of fuel oil used, and 25 sixth, to make a simple, inexpensive, and durable heater.

I accomplish the above objects by the mechanism illustrated in the accompanying drawing, in which—

Fig. 1 is a top plan view of my heater as 30 a small stove, showing same without a casing in full lines, and showing the casing in dotted lines. Fig. 2 is a vertical section of same on the line 2—2 of Fig. 1. Fig. 3 is a horizontal section on the line 3—3 of Fig. 2. 35 Fig. 4 is a front elevation of a furnace heater made in accordance with my invention, for heating several rooms, broken away in part to show the interior construction and also broken away at the base and extreme 40 top of the casing, the view also showing a casing in full lines, and Fig. 5 is a horizontal section on the line 5—5 of Fig. 4.

Like characters of reference indicate like 45 parts throughout the several views of the drawing.

The heater body comprises side 6, of sheet or cast metal, a bottom 7 and cap 8, each with inturned marginal flanges 9 to receive the sides 6 in the manner shown; the assembly being secured as one unit by the corner shaft-bolts 10. The cap 8 has an opening over which a pipe-collar 11 is bolted.

The side 6 has an opening through which 50 an oil burner 12 of any desired type is introduced, and through which a basket 13, containing an assembly of fire-bricks or other

heat retaining elements 14, is placed above the burner and is adjusted. The basket may be made out of perforated metal as shown in Fig. 2 or out of woven wire as shown in Fig. 4. It is suspended by any suitable means, such as by hooks 15 from perforated lugs 16 depending from the cap 8, as shown. This opening in the side 6 is closed by a door 17, shown as an upwardly sliding door in Figs. 1, 2 and 3, and as a hinged door in Figs. 4 and 5.

The bottom 7 is preferably sloped from the sides of the body toward the center, and at the lowest portion a trough 17' is formed which slopes toward the rear end of the heater where there is a hole through the bottom in the trough connecting with a drain pipe 18 under the stove. Any overflow of oil from the burner drains into the trough 17', and from it through pipe 18 to a suitable holder from which it is used over again in the burner. The base sets on feet 19, and under it are a plurality of arms 20, which are pivoted to the bottom 7 to enable the arms to fold back under said bottom when not in use, and to be swung out as supports for a casing 21 when such an adjunct to the heater is desired. The ends of the casing are fastened by bolts, rivets, or screws to 85 flanges 22, from the front wall.

I will now describe a very important feature of my invention, i. e., vertical air tubes 23, which connect openings through the bottom 7 with registering openings through the cap 8. These tubes take the cold air which settles by gravity nearest the floor, and conduct it through the body of the heater where it is made hot by the heat from the burner and stored heat radiated from the contents of the basket 13, and discharge it through the top of the heater. A plurality of these tubes is shown in two rows, in Figs. 1 to 3, inclusive, and arranged in a circle in Figs. 4 and 5, the shape of the stove being obviously optional with the designer, and the number of tubes dependent upon the size of the heater required and perhaps other conditions.

In order to insure an upward flow of air 105 through the tubes 23 I prefer to expand them upwardly—that is, make them of greater diameter at their tops than at their bottoms. They are assembled at each end around inturned collars 24 from the top and bottom, respectively, of the heater.

Having thus fully described my invention,

what I claim as new and wish to secure by Letters Patent, of the United States, is—

1. In an oil heater, a body comprising a top, bottom, and side, said bottom having a plurality of openings and said top having an equal number of openings, and tubes connecting each opening in the bottom with a corresponding opening in the top, said tubes being of increasing area in cross section from top to bottom, a source of heat on or near the bottom, a basket above the source of heat containing a material to store heat, said source of heat and basket being surrounded by said tubes.
2. In an oil heater, a body comprising a top, bottom, and side, said bottom having a plurality of openings and said top having an equal number of openings, and tubes connecting each opening in the bottom with a corresponding opening in the top, said tubes

being of increasing area in cross section from top to bottom, and an oil burner near the bottom, and a basket above it containing fire brick or the like and surrounded by said tubes.

3. In an oil heater, a body comprising a top, bottom, and side, said bottom having a plurality of openings and said top having an equal number of openings, tubes connecting each opening in the bottom with a corresponding opening in the top, an oil burner near the bottom a basket above the burner containing fire brick or the like and surrounded by the tubes and an oil trough below the burner also surrounded by the tubes and discharging outside of the body.

Signed at Indianapolis, Indiana, this the 16th day of September, 1922.

THOMAS F. HATTON.
